CLAIM

The ornamental design for a voltage suppressor recessed receptacle, as shown and described.

DESCRIPTION

FIG. 1 is a rear perspective view of an assembled voltage suppressor recessed receptacle employing my new design.

FIG. 2 is a top view of FIG. 1.

FIG. 3 is front perspective view of the voltage suppressor recessed receptacle of FIG. 1.

FIG. 4 is a front side view of FIG. 1.

FIG. 5 is a back side view of FIG. 1.

FIG. 6 is a left side view of FIG. 1.

FIG. 7 is a right side view of FIG. 1.

FIG. 8 is the voltage suppressor recessed receptacle of FIG. 1 shown separately with the cover removed for clarity of detail.

FIG. 9 is a top view of FIG. 8.

FIG. 10 is a front side view FIG. 8.

FIG. 11 is a back side view of FIG. 8.

FIG. 12 is left side view of FIG. 8.

FIG. 13 is a right side view FIG. 8.

FIG. 14 is a perspective view of the cover for the voltage suppressor recessed receptacle of FIG. 8, shown separately for clarity of detail.

FIG. 15 is a top view of FIG. 14.

FIG. 16 is bottom view of FIG. 14.

FIG. 17 is a right side view of FIG. 14.

FIG. 18 is a left side view of FIG. 14.

FIG. 19 is top view of FIG. 14; and,

FIG. 20 is a bottom view of FIG. 14.

The broken line showing an example of a sectional plate incorporating the voltage suppressor recessed receptacle is for illustrative purposes only and forms no part of the claimed design.
